United States Patent Office

Des. 227,934
Patented July 24, 1973

227,934

PUMP

Jerry L. Campbell, 7399 Claret Circle, Salt Lake City,
Utah 84121, and Farral D. Gay, Jr., 6843 South
2850 West, West Jordan, Utah 84084

Filed Nov. 26, 1971, Ser. No. 202,737

Term of patent 14 years

Int. Cl. D15—02

U.S. Cl. D65—1 R

FIG 1

FIG 4

FIG 3

FIG 5

FIG. 1 is a perspective view taken from slightly above and to one side of the junction of a pair of side walls;

FIG. 2, a top plan view;

FIG. 3, a side elevation view taken from one side;

FIG. 4, a similar view taken from another side; and

FIG. 5, a similar view taken from the remaining side.

We claim:

The ornamental design for a pump, substantially as shown.
